CLAIM

The ornamental design for ultrasonic probe connector, as shown and described.

DESCRIPTION

FIG. 1 is a perspective view of an ultrasonic probe connector showing our new design;

FIG. 2 is a front view thereof with explanatory cut lines 8—8 and 9—9;

FIG. 3 is a right side view thereof with explanatory cut lines 10—10;

FIG. 4 is a left side view thereof;

FIG. 5 is a top plan view thereof;

FIG. 6 is a bottom view thereof;

FIG. 7 is a rear view thereof;

FIG. 8 is a cross sectional view taken along 8—8 omitting inner mechanisms;

FIG. 9 is a cross sectional view taken along 9—9 omitting inner mechanisms;

FIG. 10 is a cross sectional view taken along 10—10 omitting inner mechanisms; and,

FIG. 11 is a perspective view showing the knob in turn position.
